VALVE

Reynold T. Hedfield, Chicago, Ill., assignor to Jas. P. Marsh Corporation, Chicago, Ill., a corporation of Illinois

Application May 10, 1940, Serial No. 334,305

5 Claims. (Cl. 236—64)

This invention relates to valves, valve assemblies and casings therefor, and more particularly to vent valves for radiators and the like for use in connection with steam or hot water heating systems whereby air may rapidly be eliminated from the system and the valves may operate automatically to prevent the escape of steam or water.

The subject matter of this application is similar to that disclosed in U. S. Patent No. 2,287,- 10 075.

The invention has for an object the provision of highly efficient, inexpensive, and rugged valve devices of this character.

An object of the invention is the provision of improved valve casings formed of aluminum, zinc, tin, or other flowable metal and having a heavy end wall and thin side walls, the side walls being reinforced by suitable strengthening ribs arranged to impart an artistic and attractive design to the exterior of the casing and at the same time materially reinforce the thin walls thereof. It is, of course, necessary that valve casings of the character set forth above have sufficient strength and rigidity to withstand accidental blows and shocks so as to prevent damage to the valve mechanism within the casing, and accordingly valve casings constructed in accordance with the present invention are preferably provided with heavy or thick end walls which in some instances may be apertured to receive suitable adjusting means, the thickness of the end wall being greater than the range of adjustment so that the adjusting means is at all times retained within the confines of the wall.

Metal such as aluminum, zinc, tin, and the like, particularly aluminum, which constitutes the preferred metal used in the casings of the present invention, cannot readily be welded or soldered, and accordingly difficulties are encountered in assembling such valve casings on the valve mechanisms to be enclosed thereby. It is, therefore, another object of this invention to provide a casing which may readily be so assembled together with a method of assembly by virtue of which the casing is accurately positioned and permanently secured in the desired position relative to the valve mechanism.

A further object of the invention is to provide a vent valve having adjustable float means for controlling the vent and in which the float means is expandable for closing the vent in response to predetermined temperature within the valve chamber.

It is also an object to provide a valve of the character described in which the position of the float with respect to the vent may accurately be adjusted before complete assembly of the valve and wherein the adjusting means is inaccessible after the valve has been permanently assembled and sealed for use.

The invention also provides a valve structure in which the float may be adjusted before complete assembly or may be adjusted through a suitable opening after complete assembly and after which latter adjustment the opening may permanently be sealed.

It is also an object to provide a sectional valve body in which one of the sections is provided with a vent opening and means for adjusting a float therein relative to the vent opening and also in which the float adjusting mechanism is inaccessible when the sections are secured together and sealed to form a float chamber having a single inlet adjacent one end and a vent opening adjacent the other end.

A further object is the provision of a valve of the character described having a sectional float chamber with a float therein for controlling a vent from said chamber and an outer casing and in which the float is adjustable by suitable means accessible from the bottom of the casing and in which the adjusting means may be made inaccessible by suitable sealing of the adjusting device in the bottom of the casing.

A further object is the provision of a valve of the character described having a float chamber comprising upper and lower sections secured together and with a float therein and novel means for adjusting the float with respect to a vent controlled thereby and in which the float adjusting means is supported entirely by the lower float chamber section; also in which a float adjusting screw extends through, or is accessible through, an opening in the bottom of the assembled valve and may be made inaccessible by suitably sealing the opening to condition the valve for use.

Further objects will be apparent from the specification and the appended claims.

In the drawings:

Fig. 1 is a perspective view of one embodiment of a valve casing forming a part of this invention.

Fig. 2 is an axial sectional elevation of a completely assembled valve.

Fig. 3 is an axial sectional view of the valve chamber and float mechanism and is taken on a

line substantially corresponding to line 3—3 of Fig. 2.

Fig. 4 is an enlarged view of the float adjusting device and illustrates the method of sealing the adjusting screw and the float chamber.

Fig. 5 is an axial sectional view similar to Fig. 2, but illustrates a slightly different embodiment of adjusting mechanism.

Fig. 6 is a fragmentary sectional view taken on a line substantially corresponding to line 6—6 in Fig. 5.

Fig. 7 is a perspective view of the supporting means for the float adjusting screw.

Figs. 8 and 9 are side elevations of bottom inlet valves, partially in section, and illustrate the method of securing casings of the type shown in Fig. 1 to bottom inlet valves.

Referring to the drawings in detail, the valve casing 1 illustrated in perspective in Fig. 1 as comprising a preferred embodiment of the invention may be formed of aluminum or similar light flowable metal of the type hereinbefore indicated and comprises a heavy upper end wall 2, from which extends a substantially cylindrical thin side wall 3. The valve casing is provided with a plurality of longitudinal ribs 4 which extend substantially throughout the length of the thin side walls and over a portion of the outer surface of the thick end wall 2. The upper ends of the ribs 4 terminate in an annular raised portion 5 formed on the upper surface of the end wall. In this embodiment of the invention, the ribs 4 are symmetrically arranged in four groups of three ribs each, the central rib of each group preferably being somewhat wider than the outer ribs. An artistic design is thus formed on the valve casing and the relationship of the ribs to the raised circular portion 5 of the end wall completes the design and at the same time the ribs and their distribution materially strengthen the thin side walls, which otherwise are of insufficient strength to resist the rough usage to which such casings are often subjected. In addition to its function of co-operating with the ribs to complete the design, the circular portion 5 forms a convenient surface upon which suitable advertising or identification indicia may be located for co-operation with a vent adjusting means which may be located in an opening 6 in the end wall 2 after the entire valve is assembled.

The opening or aperture 6 extends completely through the end wall 2 centrally of the raised portion 5. It will be apparent from the drawings that the valve casing therein shown presents a very attractive appearance, and it has been found that a casing of this character, having a thick end wall for strength and relatively thin side walls for economy of material and provided with longitudinal strengthening ribs, provides a highly advantageous construction, particularly when used in connection with valve mechanisms of the type disclosed herein and which will be more fully described hereinafter.

Although it would probably be possible to form casings such as illustrated and described herein, by various casting, molding, and machine operations, such procedure would be relatively expensive, and these casings are, therefore, particularly designed for manufacture by an impact extrusion process. By means of the impacting extrusion process, castings of this character may be formed very quickly and inexpensively and by a minimum of machining and finishing operations.

The manufacturing process involves the impact extrusion of suitable flowable metals in such a

fashion as to form the completed casing with a single impact, the strengthening and decorative ribs 4 being instantly extruded integrally with the side walls during the forming operation. Additional advantages of the impact extrusion process are found in the uniformity of the finished products, the high mechanical strength obtained due to the fact that impact extruded aluminum is strain-hardened, and the low production costs involved. The casing illustrated is particularly adapted for manufacture by this process.

Although the casings are not limited to use in connection with the particular types of valve mechanisms shown, they are especially useful in connection therewith. Fig. 2 illustrates a preferred form of valve mechanism enclosed in one of the casings shown in Fig. 1 after the casing has been extruded and subjected to certain machining operations in order to adapt it for use in the manner shown. These machining operations comprise the removal of the ribs 4 from the blank for a short distance adjacent the open end of the casing so as to provide a thin end portion 7, also the provision of a notch 8 in one side of the casing adjacent the open end thereof, the formation of a plurality of small apertures 9 in one side of the casing, preferably along one of the ribs 4, and the formation of the heretofore mentioned aperture 6 in the end wall 2, the aperture 6 preferably being formed so as to provide an annular shoulder 10, as best illustrated in Fig. 2.

Referring particularly to Figs. 2, 3, and 4, the embodiment illustrated therein shows a completely assembled valve, including a casing such as illustrated in Fig. 1, and comprises a valve chamber 11 formed of two sheet metal cup-like members 12 and 13 arranged to telescope each other as shown and which are permanently secured together and sealed at 14 by any suitable means, preferably by soldering or any similar securing and sealing method. The upper member 12 constitutes the vent section of the chamber 11 and is provided with an axially positioned upwardly extending vent nipple 15 having an axial passage 16 therethrough and a transverse passage 17 communicating therewith and forming a pair of lateral vent openings. The enlarged upper end of the axial passage is provided with an adjusting screw 18 having an axial tip 18a adapted to control the size of the vent openings when the screw 18 is adjusted. The vent nipple 15 is preferably inserted in an axial opening in the member 12 and is soldered or brazed therein or secured in any other suitable leak-proof manner.

A sheet metal liquid control cup 19 is supported in the chamber 11 with its open end extending into the upper member 12 loosely or slidably fitting therein as shown in Figs. 2 and 3. A portion of the walls of the member 19 are indented or corrugated to provide passageways 20 (Fig. 3) to establish communication between the bottom of the valve chamber 11 and the vent outlet passage 16. The lower cup shaped member 13 of the chamber 11 has its bottom wall formed inwardly as shown to provide a re-entrant portion 21 having an enlarged axial opening therethrough to provide clearance for a downwardly extending threaded portion 22 of the liquid control cup 19 after the parts are assembled and to enable the bottom of the cup to rest snugly on the re-entrant portion 21.

The various elements are so related that, when the lower chamber member 13 is telescoped over the upper member 12, the liquid control cup 19 rests on the upper surface of the re-entrant por-

tion 21 so that these portions may later be sealed together. The cup 19 is provided with an axial adjusting screw 23 supporting a float 24, which latter may be of the usual type responsive to flotation and temperature changes to control the vent and is provided with an upwardly extending stem 25 adapted to close the vent passage 16 when the float 24 is raised by water entering the chamber 11 or when it is expanded by predetermined temperature within the valve.

The lower cup member 13 which constitutes the base or inlet section of the valve chamber 11 is provided with a laterally extending spud 26 which may be threaded as shown to enable the device to be attached to a radiator or other part of a heating system. This spud 26 may be secured and sealed in the base 13 in any suitable means, preferably by means of an inner flange 27 having lugs 28 thereon adapted to enter suitable complementary openings in the wall of the base 13, whereby the spud is accurately positioned relative to the casing. The spud may be secured in place by soldering, and a so-called siphon 29 which may be of the usual type extends through the spud 26 and is provided with an outturned retaining flange 30. A sheet metal member 31 is provided with a slot 32 to receive the end of the siphon whereby the siphon is loosely retained in position. The sheet metal member 31 is preferably soldered or otherwise secured to the spud flange 27.

In assembling the device, the float 24 is positioned in the upper cup shaped member 12 with the vent controlling stem 25 in position to control the vent opening in the usual manner. The liquid control cup 19 is then inserted with the adjusting screw 23 against the bottom of the float and the member or base 13 of the chamber 11 is telescoped over the upper portion 12 so that the end of the re-entrant portion 21 is in contact with the bottom wall of the cup 19 with the adjusting screw 23 extending through the enlarged opening therein so that this screw is accessible for adjustment after the device is assembled but before being completely sealed for use. The cup shaped chamber members 12 and 13 may then be secured together and simultaneously sealed at 14 by soldering or any other suitable method. After the unit is assembled as described, the adjusting screw 23 is accessible from the bottom of the unit for adjustment of the float, although the screw is entirely confined within the general contour of the unit. The unit may then be subjected to a predetermined temperature and an adjustment made for control of the vent in a desired manner, after which the adjusting screw may be locked and sealed simultaneously with the sealing of the joint between the bottom of the cup 19 and the re-entrant portion 21 by applying solder over the end of the screw 23 and the opening through which it extends as shown at 33. The solder 33 secures the parts together and the adjusting screw 23 is made normally inaccessible after the device is completely assembled and sealed, and the adjustment is, therefore, retained indefinitely.

The previously described outer casing 1 of impact extruded material and constructed as illustrated in Fig. 1 is arranged to telescope downwardly completely over the valve chamber as shown in Fig. 2 with the notch 8 providing clearance for the inlet spud 26. The upper edge of the notch 8 is accurately located so as to provide a stop against the spud to limit the down-

ward telescoping of the housing. The bottom of the base member 13 is preferably provided with an annular shoulder 34 to align with the bottom of the casing after it is secured thereon.

5 After the outer housing is fully telescoped over the chamber unit, the lower edges are rolled or crimped over the bottom edge of the lower cup section 13 to form a smooth rounded corner as shown at 35. This provides a completely enclosed double shell structure having no outwardly extending projections except the inlet spud 26 and the associated siphon 29.

As previously stated, the upper end of the outer casing 1 is provided with an axial opening 6 to receive the upper end of the vent adjusting screw 18, and this adjusting screw is preferably provided with a rectangular or irregularly shaped head 36 to be received within a similarly shaped opening 37 in an adjusting plug 38. The plug 38 is preferably mounted entirely within the opening 6 of the casing so that its outer surface forms a smooth continuation of the outer surface of the casing and is supported therein by means of a plate 39 secured to the end wall 2 of the casing by means of riveting lugs 40. The plug 38 is retained in assembled relation with the casing by means of a resilient split ring 41 in an annular groove 42 in the plug. When the plug with the split ring assembled in the groove 42 is pushed inwardly into the casing, the resilient split ring engages the shoulder 10 of the casing and the plug is thereby rotatably retained in position. The plug is provided with a slot 43 whereby it may easily be rotated for adjusting the vent control screw 18 and the supporting plate 39 is provided with an upwardly extending lug 44 which is adapted to be engaged by a stop 45 on the plug to thereby limit the rotation of the plug and the consequent adjustment of the vent over a predetermined range. The plug 38 and the annular ring surface 5 of the casing may be provided with cooperating indicia to predetermine the vent control by the proper setting of the plug.

45 As previously stated, the outer shell or enclosing casing 1 is provided with a series of small openings or perforations 9 which are preferably arranged in a vertical row substantially as shown in Figs. 1 and 2, whereby the perforations are at 50 progressively increasing distances from the vent openings 17. Air or other fluid discharged from the vent openings 17 expands in the upper part of the outer casing, which, after assembly, forms a muffler chamber 46, and the fluid is accordingly exhausted at reduced velocity from the perforations or ports 9. Since these ports are arranged at progressively increasing distances from the vent openings, unequal velocities of flow exist at the different ports, and the tendency of the exhaust fluid to produce audible sound is thus materially reduced. Furthermore, such sound as may be produced at the vent opening 17 is effectively dissipated by the construction of the casing 1 and the arrangement of the ports 9 relative thereto.

70 The impact extrusion casing previously described is particularly adapted for use in the relationship disclosed. Furthermore, it is preferable to provide the casing with a relatively thick upper wall adjacent the vent opening, as this construction, combined with the type of material used, augments the sound dissipating and eliminating characteristics of the muffler chamber 46 and the exhaust ports 9, the nonresilient character of the material and the thick upper wall and

reinforcing ribs tending to reduce the so-called sympathetic vibration of the casing.

Furthermore, the ports 9, by reason of their small diameters and their longitudinal arrangement and progressively increasing distances from the vent openings, tend to round off the sharp wave fronts of the sound waves initiated at the vent openings and thus further assist in providing a noiseless construction. Also, the particular type of casing provides an additional advantage in the thick upper wall in that sufficient adjusting space is provided within the confines of the wall itself so that the movable elements of the adjusting mechanism are positioned entirely within the contour of the casing and within the confines of the thick upper wall in position for adjustment of the vent openings. Thus, unsightly projections from the valve casing are eliminated.

The construction provides a large float chamber having plenty of space for air and water separation so as to minimize to a large degree float bobbing and spitting. The automatically controlling float may accurately be adjusted before or after complete assembly and a positive float action and quick response to temperature are assured, so that the vent is immediately closed when steam reaches the float chamber. Any venting rate from minimum to maximum is obtained by merely turning the plug 38 to a desired point in accordance with the indicia. An inexpensive, easily assembled, and easily adjusted double shell construction is provided in which air is vented into the muffler compartment between the shells where it expands and leaves noiselessly through the plurality of small discharge ports.

A baffle plate 47 may be mounted on the floats 10 so that the outer edges of the baffle extend over the passageways 20 between the float supporting cup 19 and the upper member 12 and 40 which are disclosed in the path of the fluid flowing through the corrugations. Thus, upon the occurrence of a sudden surge of high velocity flow of fluid through the corrugations, the impact of the fluid on the baffle 47 is effective to raise the float member 48 independently of the flotation and temperature conditions existing within the valve and thereby close the vent opening and prevent spitting of the valve.

The cup shaped float supporting member 19 surrounds the float element so as to form a float chamber of restricted capacity, and it will be apparent that, upon the accumulation of liquid within the member 19, the float will be operated by this liquid to close the vent opening. The accumulation of liquid in the cup member 19 may occur due to the deflecting action of the baffle 47, which tends to deflect entrained liquid flowing through the corrugations or passages 20 so that this liquid accumulates in the cup 19.

The condensation of steam in the upper portion of the valve chamber 11 will also result in accumulation of liquid within the cup 19 and the baffle 47 is provided with a plurality of apertures 48 which permit the condensate to enter the cup member 19 from the upper end thereof. Provision of the restricted capacity float chamber formed by the cup 19 is highly effective in preventing bobbing of the float due to sudden changes in the liquid level within the valve chamber or due to surges.

The float supporting cup 19 is provided with a small aperture 49 adjacent the bottom thereof, through which aperture liquid accumulated in the cup 19 may return to the lower portion of

the valve chamber 11, wherefrom it is discharged through the siphon 29. That portion of the cup 19 below the aperture 49 is at all times filled with liquid, and accordingly a very small additional amount of liquid will raise the float sufficiently to close the vent opening. Thus, upon a sudden surge of the fluid flowing through the passages 20 of sufficient velocity to effect operation of the baffle 47 so as to close the vent opening, there may be a considerable quantity of entrained liquid deflected into the cup 19, and the consequent rise in the level of the liquid within the cup will serve to hold the vent closed for a short interval following such a high velocity surge. Whenever the liquid level in the valve chamber 11 rises above the aperture 49, the liquid flows into the cup 19 so as to raise the float 24 and effect closure of the vent opening if the vent is not already closed due to temperature conditions existing within the valve chamber.

The capacity of the aperture 49 is considerably less than the drainage capacity of the siphon 29, and, accordingly, when conditions are such that liquid is being withdrawn from the valve chamber through the siphon tube at a greater rate than it is being accumulated in the chamber, so that the liquid level falls below the aperture 49, liquid drains from the cup 19 at a rate which is less than the rate of discharge of liquid from the valve chamber. Therefore, sufficient liquid will be retained in the cup 19 and slowly drained therefrom to maintain the vent closed until substantially all of the liquid within the chamber 11 has been withdrawn through the siphon. This insures that, when the liquid level within the valve chamber 11 has fallen approximately to that level at which the vent would open if the cup 19 were not provided, sudden changes in liquid level will not effect bobbing of the float, since sufficient liquid is retained in the cup 19 to hold the float firmly in vent closing position.

The embodiment illustrated in Figs. 5, 6, and 7 comprises a valve chamber 11a which is very similar to that previously described and is formed of two cup-shaped sheet metal members 50 and 51 arranged to telescope each other, as shown, and which are permanently secured together and sealed at 52, preferably by soldering or other suitable method. The upper member 50 constitutes the vent section and is provided with an axially positioned upwardly extending nipple 53 having an axial passage 54 therethrough and lateral vent openings 55 communicating therewith. The upper end of the axial passage is threaded and provided with an adjusting screw 56 for controlling the size of the vent openings.

The lower cup member or base 51 is provided with a spud 26a having a siphon 29a supported therein, and this spud and siphon may be similar to that previously described and may be secured in the base in the same manner. The bottom of the base 51 is preferably provided with an annular shoulder 57 and an axial re-entrant depression 58 having an opening 59 therethrough of a size adapted to receive a screw driver for adjusting the valve during test in a manner which will later be described. After the adjustment has been made, the opening 59 is closed by means of a plug 60 which may be secured in the opening and properly sealed by means of solder or the like, as illustrated at 61.

A valve supporting strap or yoke 62 is formed substantially as illustrated in Fig. 7 and provided with a raised central portion 63 and upwardly

extending arms 64. The arms 64 are preferably arcuate to conform with the contour of the inner surface of the base 51, whereby the yoke fits snugly therein and may be retained in position by friction against the side walls. During assembly, the yoke is first inserted in the base and the upper member 50 then telescoped therein until it rests on the ends of the arms 64 of the yoke, thereby limiting the telescoped relationship of the parts, whereby, after the cup members are secured together, the yoke is retained in position between the bottom of the base 51 and the lower edge of the upper member 50. The central raised portion of the yoke 62 is provided with an axial threaded opening 65 to receive an adjusting screw 66 on which the float 24a is supported, the float, of course, being provided with the usual stem 25a adapted to control the vent opening. The float 24a is of the same type as previously described and is expansible in response to predetermined temperature.

The construction disclosed provides a transversely extending raised float support or yoke having a float adjusting screw therein in alignment with the base opening 59, and the entire support is mounted in the lower base and retained therein by the upper member 50. Therefore, after this inner mechanism is assembled, the sub-assembly may be tested and the screw 66 adjusted to provide a predetermined vent control by the float 24a, after which test and adjustment the plug 60 may be inserted and the opening sealed as previously described, whereby the adjusting screw is normally inaccessible after complete assembly and sealing.

The outer casing 1a of impact extruded metal, which may be substantially identical with the casing 1 previously described, may then be telescoped downwardly completely over the valve chamber 11a, as shown, and positioned thereon and secured in the same manner as previously described by rolling or crimping the edges 35a over the bottom edge of the base 51, as shown. This provides a completely enclosed double shell structure having no outwardly extending projection except the inlet spud 26a and the associated siphon 29a.

The upper end of the vent adjusting screw 56 is positioned within the opening 6a in the thick base 2a of the outer casing. A washer 67 is provided under the head of the screw to close the opening 6a and a spring 68 retains the screw in any adjusted position. The head of the screw 56 is provided with a pointer portion 69 which co-operates with suitable indicia on the upper end of the casing to predetermine the vent adjustment. The thick end wall 2a of the casing enables the screw head to be positioned at all times within the outer contour of the casing. This double shell valve and the type of casing used provides all of the desirable structural and sound eliminating characteristics which have previously been described in connection with the other embodiments disclosed herein.

The valve structures thus far referred to are provided with laterally extending spuds arranged to co-operate with a suitable slot or notch in the outer casing so as to properly position the casing. The same impact extruded casing may also be applied to valves known as straight valves, wherein the inlet spud extends axially from the lower end wall of the valve chamber. Such a construction is illustrated in Figs. 8 and 9, wherein a tubular valve chamber, similar to those previously described, is provided, the valve chamber

in this construction comprising an upper cup shaped member 70 and a lower cup shaped member 71, the bottom wall of the latter member being shaped as shown to provide an axially extending inlet spud 72. Since the inlet spud 72 in this form of valve may interfere with the float supporting and adjusting structures shown in Figs. 2 to 7, inclusive, I prefer in this type of valve to use the construction disclosed and claimed in the above referred to U. S. Patent No. 2,287,075.

In order to position the outer valve casing 1b in proper relation to the valve chamber and the associated adjusting mechanism, the inlet spud 72 is provided with a laterally extending annular flange or shoulder 73 initially formed substantially as shown in Fig. 8. When the outer casing 1b, which may be identical with the casing shown in Fig. 1, except that the notch 8 is omitted, is telescoped over the valve chamber, the flange 73 engages the lower end of the casing 1b so as initially to position the casing in predetermined relation to the valve mechanism. Permanent locking of the casing in this position may then be accomplished simply by spinning or pressing the lower edge of the casing side wall inwardly so as tightly to engage a suitable rounded shoulder 74 on the lower end of the base member 71, and by then spinning or pressing upwardly the flange 73 so as to snugly overlap the end of the casing 64, as shown in Fig. 9, whereby the casing 1a is firmly locked in position with respect to the valve mechanism. It will be apparent that in all of the embodiments shown the type of casing used and the method of securing the outer casing to the valve mechanism results in a smooth finished appearance, since no extending rivets or locking members are necessary.

It is intended, of course, that the invention should not be limited to the specific embodiment or embodiments disclosed herein, since many modifications may be made, and it is contemplated, therefore, by the appended claims to cover any such modifications as fall within the true spirit and scope of this invention.

Having thus described this invention, what is claimed and desired to be secured by Letters Patent is:

1. In combination, an air valve mechanism including a substantially tubular valve chamber having adjustment means extending axially from one end and an inlet stud projecting from a side of said chamber adjacent the other end, an outer housing comprising an aluminum shell telescoped over said chamber having a notch for receiving said projecting stud, said aluminum shell having a thick end wall apertured to receive said adjustment means whereby said adjustment means is accessible for manipulation, engagement of said stud with the end of said notch being effective initially to position said shell on said chamber so that said adjustment means is contained within the aperture in said thick end wall throughout its range of adjustment and so that the open end of said shell extends beyond said other end of said valve chamber, the extending end of said shell, upon being pressed inwardly tightly to engage said other end of said valve chamber, permanently securing said outer housing in said initially determined position.

2. A vent valve comprising a valve chamber having a bottom inlet and a top vent, a condition-responsive element in said chamber in vent controlling relationship, a bridge frictionally secured in said chamber between the bottom wall

and said element, said bridge comprising spaced apart arms engaging opposed side walls of said chamber and a portion extending transversely of said arms in a plane intermediate the upper and lower ends of said arms, and means on said transversely extending portion of said bridge for adjusting the controlling relationship of said element to said vent.

3. A vent valve comprising a valve chamber having a bottom inlet and a top vent, a bridge extending upwardly from the bottom wall of said chamber comprising a transverse portion supported on opposed arms, said arms extending downwardly from said bridge to said bottom wall and then upwardly to a point beyond said transverse portion, whereby said transverse portion lies in a plane intermediate the upper and lower ends of said arms, an axial screw supported on said transverse portion of said bridge, and a temperature responsive float valve on said screw in adjustable vent controlling relationship to said vent.

4. A vent valve comprising an upper section and a lower section sealed together to form a valve chamber having a vent in the upper section and an inlet in the lower section, a temperature responsive float valve in said chamber, a bridge in said lower section having a transverse portion supported on opposed arms in a plane intermediate the ends of said arms, said arms extending along the walls of said lower section whereby said bridge is frictionally retained against rotation

in said lower section by engagement with the walls thereof, the lower ends of said arms engaging the bottom wall of said lower section and the upper ends of said arms being positioned to engage the lower edge of said upper section whereby said bridge is retained against axial movement in said lower section, and means on said transverse portion of said bridge for adjusting the controlling relationship of said float valve to said vent.

5. In combination, air valve mechanism including a substantially tubular valve chamber having adjustment means extending axially from one end and a projection extending outwardly from a side of said chamber adjacent the other end, an outer housing telescoped over said chamber having a notch for receiving said projection, said outer housing having a thick end wall apertured to receive said adjustment means whereby said adjustment means is accessible for manipulation, engagement of said projection with the end of said notch being effective initially to position said housing on said chamber so that said adjustment means is contained within the aperture in said thick end wall throughout its range of adjustment and so that the open end of said housing extends beyond said other end of said valve chamber, the extending end of said housing upon being pressed inwardly tightly to engage said other end of said valve chamber permanently securing said outer housing in said initially determined position.

REYNOLD T. HEDFIELD.
